US0D1096168S

(12) **United States Design Patent** (10) Patent No.: **US D1,096,168 S**
 Roberts et al. (45) Date of Patent: ** Oct. 7, 2025

(54) **ORGANIZING GRID FOR STORAGE CASE**(71) Applicant: **Magpul Industries Corp.**, Austin, TX (US)(72) Inventors: **Timothy Eric Roberts**, Broomfield, CO (US); **Michael Werner**, Arvada, CO (US); **Clinton Wade Lynch**, Erie, CO (US); **Jacob Blick**, Superior, CO (US); **Kellen Cooper Sansone**, Denver, CO (US)(73) Assignee: **Magpul Industries Corp.**, Austin, TX (US)(**) Term: **15 Years**(21) Appl. No.: **29/978,279**(22) Filed: **Dec. 12, 2024**

CLAIM

The ornamental design for an organizing grid for storage case, as shown and described.

DESCRIPTION

FIG. 1 is a left, front, top perspective view of the organizing grid for storage case;

FIG. 2 is a front elevation view of the organizing grid for storage case;

FIG. 3 is a rear elevation view of the organizing grid for storage case;

FIG. 4 is a left elevation view of the organizing grid for storage case;

FIG. 5 is a right elevation view of the organizing grid for storage case;

FIG. 6 is a top view of the organizing grid for storage case;

FIG. 7 is a bottom view of the organizing grid for storage case;

FIG. 8 is a left, front, top perspective view of a second embodiment of the organizing grid for storage case;

FIG. 9 is a front elevation view of the second embodiment of the organizing grid for storage case;

FIG. 10 is a rear elevation view of the second embodiment of the organizing grid for storage case;

FIG. 11 is a left elevation view of the second embodiment of the organizing grid for storage case;

FIG. 12 is a right elevation view of the second embodiment of the organizing grid for storage case;

FIG. 13 is a top view of the second embodiment of the organizing grid for storage case; and,

FIG. 14 is a bottom view of the second embodiment of the organizing grid for storage case.

The dash-dot broken lines depict portions of the organizing grid for storage case that form no part of the claimed design. The remaining dash-dot broken lines depict claim boundary limits and form no part of the claimed design.
